CLAIM

The ornamental design for a shoe as shown and described.

DESCRIPTION

FIG. 1 is a front perspective view of a shoe showing my new design;

FIG. 2 is a side view thereof;

FIG. 3 is a rear perspective view thereof;

FIG. 4 is a rear view thereof;

FIG. 5 is an opposite side rear perspective view thereof;

FIG. 6 is an opposite side view thereof; and,

FIG. 7 is an opposite side front perspective view thereof. The broken lines immediately adjacent to the shaded area represent the bounds of the claimed design and form no part thereof. The unshaded regions form no part of the claimed design. The broken lines and unshaded areas depicting the remainder of the shoe form no part of the claimed design.

1 Claim, 7 Drawing Sheets(56)
